UNITED STATES PATENT OFFICE.

JAMES BRUCE MASON, JR., OF NASHVILLE, TENNESSEE.

DISPLAY CASE FOR PENCILS.

Application filed April 30, 1921. Serial No. 465,661.

To all whom it may concern:

Be it known that I, JAMES BRUCE MASON, Jr., a citizen of the United States, residing at Nashville, in the county of Davidson and

5 State of Tennessee, have invented certain new and useful Improvements in Display Cases for Pencils, of which the following is a specification.

The object of this invention is to provide 10 an attractive and substantial case or container for displaying pencils, pens and the like, which is portable, may be placed where desired for displaying the contained articles, and which may be closed and securely locked.

15 In carrying out my invention I provide a case preferably made for the most part of metal and in the form of a pencil. The case is divided into sections hinged together so that it may be opened and closed, and it is 20 provided with racks for the articles to be displayed. The point of the pencil-shaped case and the opposite end of the case have a threaded engagement with the body of the case and are so mounted that they may over- 25 lap the hinged section of the case and hold it tightly closed.

In the accompanying drawings:—

Figure 1 shows a longitudinal, central section through a display case for pencils, eman- 30 bodying my improvements.

Figure 2 is a perspective view, showing how the body of the case is divided and how the case, when closed, may be locked.

Figure 3 shows a section on the line 3—3 35 of Fig. 1.

Figure 4 is a perspective view of one of the rack members.

The display case, made in accordance with 40 my invention, is especially designed for exhibiting mechanical or automatic pencils, but may be used for displaying fountain pens, and other such articles.

The case as a whole is made in the shape 45 of a mechanical or automatic pencil of well known construction and is preferably made of metal which may be nickel-plated.

The central or body portion A of the case, which is cylindrical, is divided into two semi-cylindrical parts, hinged together at a. 50 Within these sections of the casing there are secured rack members B, each member comprising a semi-circular band b and clamping devices b'. The rack members are preferably attached to the sections A by 55 providing said sections with clips c which are adapted to engage the rack members in

the manner clearly shown in Fig. 1. The middle part of the case is preferably made of sheet metal and may be lined with suitable material. It is preferably divided by 60 partitions D into two parts, as shown. The ends of the hinged section may be strengthened or reinforced by wood or other material, as indicated at E.

At one end of the body there is a circular 65 end-piece F and at the other end there is a similar end-piece G. These parts are arranged outside the reinforcing pieces E. The ends of the sections A are threaded, as indicated at g, h. At one end of the case 70 there is a removable cap H which is shaped like a pencil point. It has a threaded engagement at h with one end of the body A and when screwed home to the full extent it overlaps the body A at h'. At the opposite 75 end of the display case there is a cap L which has a threaded engagement with the body at l and when this cap L is screwed home to the full extent it overlaps the body A at l'.

80 As shown in Figure 1, the case is closed and locked, and is pencil-shaped although, of course, of large dimensions and adapted to hold a large number of pencils, pens and the like. By unscrewing the caps H and L 85 to a sufficient extent the inner ends of these caps may be withdrawn from the body A and the upper section of the body may be swung back so as to display the articles within the case. The case may be closed by 90 swinging the upper section of the body on its hinges, bringing the opposite edges together at a and then screwing the caps H and L until their inner portions overlap the hinged part of the body. When this is done the case 95 is securely closed and cannot be opened until the caps H and L are properly operated.

I claim as my invention:—

1. A display case for pencils and the like, comprising a hollow, cylindrical body made 100 in two sections, one of which is hinged to the other and provided with racks on the inside to hold articles for display, and screw caps at opposite ends of the case which overlap the opposite ends of the hinged sections 105 of the body and hold it closed but which may be withdrawn therefrom while still connected with the body.

2. A display case for pencils and the like, comprising a hollow, cylindrical body made 110 in two sections hinged together and provided with racks on the inside, reinforcing

members at the ends of the body provided with screw threads on their peripheries, and caps at opposite ends of the case having a screw-threaded connection with said end members, and having portions which overlap the opposite ends of the hinged section of the case.

3. A display case for pencils and the like having a cylindrical body portion made in two sections hinged together and provided

with reinforcing members at their ends, rack members detachably connected with the inside of the casing sections, and caps at opposite ends of the casing having a threaded connection with the end members thereof and having parts which overlap the hinged section of the body of the casing.

In testimony whereof, I have hereunto subscribed my name.

JAMES BRUCE MASON, JR.
